William Dillard, Jr., New York, N. Y.

Application June 19, 1948, Serial No. 147,078

Term of patent 3½ years

(Cl. D29—23)

To all whom it may concern:

Be it known that I, William Dillard, Jr., a citizen of the United States, residing at New York, in the county of New York and State of New York, have invented a new, original, and ornamental Design for a Wall Plaque or Similar Article, of which the following is a specification, reference being had to the accompanying drawing, forming a part thereof.

In the drawing:

Fig. 1 is a front perspective view of a wall plaque or similar article, showing my new design; and

Fig. 2 is a rear perspective view of the same.

I claim:

The ornamental design for a wall plaque or similar article, as shown.

WILLIAM DILLARD, JR.
